Primary Examiner — Melanie Pellegrini

(57) **CLAIM**

The ornamental design for a finger ring as shown and described.

DESCRIPTION

1. Finger ring

1.1 : Perspective view 1

1.2 : Perspective view 2

1.3 : Front

1.4 : Back

1.5 : Top

1.6 : Bottom

1.7 : Right

The broken lines in the reproductions form no part of the claimed design; the dot-dash broken lines denote the boundary between the claimed portion and the unclaimed portion, and form no part of the claimed design; the left view is omitted because it is a mirror image of the right view.

1 Claim, 7 Drawing Sheets
